DESIGN FOR A MUSICAL INSTRUMENT CASE

Harry Buegeleisen, New York, N. Y.

Application December 24, 1937, Serial No. 73,845

Term of patent 3½ years

To all whom it may concern:

Be it known that I, Harry Buegeleisen, a citizen of the United States, residing at New York, in the county of New York and State of New York, have invented a new, original, and ornamental Design for a Musical Instrument Case, of which the following is a specification, reference being had to the accompanying drawing, forming part thereof.

Fig. 1 is a front perspective view of the musical instrument case, showing my design; and
Fig. 2 is an end elevational view thereof.

I claim:

The ornamental design for a musical instrument case as shown.

HARRY BUEGELEISEN.
